UNITED STATES PATENT OFFICE

JESSE E. BERKHEIMER, OF TACOMA, WASHINGTON

INTERLOCKING SHINGLE

Application filed August 3, 1931. Serial No. 554,692.

The invention pertains to interlocking shingles, particularly to such shingles as are made of so-called prepared or composition roofing, consisting of a heavy felt or fabric body saturated and coated with bituminous composition, and generally faced with fine granules of mineral matter.

The principal object of my invention is to provide composition shingles of such construction that they can be laid in interlocking relation, with the lower corners of each shingle held tightly down so that the butts cannot be blown, slipped or pulled out of position after the roof is put on; that when so laid the shingles will have sufficient lap at all points to produce a rain and weather tight roof covering; that the lower end of each shingle may freely expand or contract without wrinkling or buckling because of varying temperature or the shrinkage of the underlying roof sheathing.

Another object of the improved shingle is to economize in the use of roofing material of which the shingles are made. A still further object is to produce a roof covering that will present an ornamental appearance when laid in one uniform color, and that can be made more attractive and interesting when shingles of different colors are used.

I attain these and other objects by means of the novel features of construction herein-after described and as shown in the accompanying drawing, which illustrates the preferred form of the invention, and in which—

Figure 1 is a plan view of a half shingle to be used as a starter at the end of the roof.

Figure 2 is a plan view of the whole shingle to be used throughout the body of the roof when laid.

Figure 3 is a plan of part of a roof on a smaller scale, and shows the shingles laid in interlocking relation and the method of interlocking them.

Similar characters refer to similar parts in each of the views.

Referring to the drawing, it will be seen that the starter shingle 1 and the body shingle 2 shown respectively in Figs. 1 and 2 are of uniform length. They are each designed to be 18 inches long from bottom to top with a purpose of cutting them from a one-half width of prepared roofing from which they are made, the standard width of which is 36 inches. The width of the shingle may be optional with the manufacturer. The body shingle shown in Fig. 2 is drawn to be 16 inches wide and the starter shingle shown in Fig. 1 is made one-half as wide and may be made by cutting the body shingle into two equal parts, thus requiring but one form and size of shingle to be manufactured.

The interlocking of the shingle is attained by means of a narrow slit 3 with a round terminal 4 cut diagonally inwardly and upwardly from each side and near the butt end of each shingle. The slits determine the width of the side overlap of the shingles with each other and provide the means whereby the butt end of each shingle can be securely interlocked underneath each adjacent side unit. At the top of each shingle and in lateral alignment with the round terminals 4—4 are placed alignment markers 5—5. These markers are slight indentations into the face of the shingle and are designed to indicate when each shingle is in lateral alignment with the adjacent side course of shingles as the roofer places each shingle into interlocking position prior to nailing it in place. The depth of the slits 3 are shown in the drawing to be approximately $3\frac{1}{2}$ inches which is known to be ample to make a rain-tight roof. This depth may be made more or less to meet the requirements of different climates where there is a difference in the violence of storms, degrees of temperature and the amount of rain-fall.

The horizontal overlap in laying composition shingles must vary with the slope or

pitch of the roof. To indicate the varied overlaps, three pairs of markers, 6—6, 7—7 and 8—8 are indented in the edge face of each shingle. The first pair 6—6 are to be used when shingling a roof of 45 degrees or more; the pair 7—7 are to be used when shingling a roof having a pitch of 30 to 45 degrees; and the pair 8—8 are to be used when shingling a roof of less than 30 degrees 10 pitch.

Having described the construction of the newly invented interlocking shingle, the manner of putting them on the roof will be described by referring to Fig. 3. Before 15 beginning to lay the shingles in place, a starting strip 9 made of one-half width of prepared roofing is laid along the eave of the roof and in alinement therewith. This with the butts of the eave shingles are to be securely nailed in place with flat header nails 10. A starter shingle 1a is made by cutting off the butt end of a starter shingle 1 just above the round end 4 of the slit 3. Above this is continued a series of starter shingles 25 1b, 1c, 1d and so on up the end or rake of the roof, each shingle being placed with an overlap of $3\frac{1}{2}$ inches over the shingle below. These shingles are nailed at the top and along the roof edge as indicated and 30 shown. The overlap is designed for a 45 degree roof pitch.

The first body course of shingles is now started by laying the shingle 2 to interlock with shingle 1a so that 1a will engage the 35 slit 3 in shingle 2, and shingle 2 will engage the slit 3 in shingle 1b so that the butt corner of shingle 2 will slip under shingle 1a and the same part of shingle 1b will slip under shingle 2. The side marker 6 of shingle 40 1b is to be in alinement with the top of shingle 2 and the top marker 5 in alinement with the edge of one 1b as will be seen at shingle 1e. The top of shingle 2 is now nailed near the top and near the edge of shingle 1b and 45 also near the top right hand corner the same as shown in the top shingles of this Fig. 3. The other shingles of this lateral course will be continued in the same manner of interlocking and nailing in place.

50 The second lateral body course will be started by cutting off the butt end of a shingle 2 similar to the starter 1a and laid in place to engage the slit 3 of the eave shingle of the first lateral course as shown on the 55 drawing and the course continued up, each shingle being interlocked, laid and nailed as shown and described in the first lateral course. The roofer can simplify his work by laying several courses at a time, the leading course being one shingle in advance of the following course.

The manner of laying and inserting the shingles in place is indicated at the right of Fig. 3, where shingles 2x and 2y are shown 60 detached and the position to which they are to

go into the body of the roof indicated by broken lines.

It will be seen that the starting strip 9 will be exposed at the bottom of each alternate lateral course of shingles and that a large 70 part of the center of each body shingle will have its one thickness only used as the roof covering, thus making a great saving of roofing material. In a 45 degree roof approximately 30 per cent of the roof will have no overlap. There will be 72 shingles of the 16 x 18 inch size required to cover 100 square feet of roof as shown in Fig. 3, in which only 144 square feet of roofing material will be used. This will make a great saving of material and labor when compared with roofs 80 put on with other shingles of this kind now in general use.

My improved shingle can be economically manufactured because of there being no waste 85 of material and of the shingles being rectangular in form. No complicated machinery will be required to make them. The interlocking diagonal slits can be cut with a very simple cutting device. The shingles being rectangular in form can be easily crated for shipping, and no expert roofer will be required to put them together on the roof. They will be useful in rural localities as well 90 as in the cities where economy in material and labor are to be considered.

The shingles are to be made of any standard composition roofing material, but materials of the best quality are recommended, those made most fire-proof, being preferred 100 to guard against fire hazard.

It is to be understood that I do not limit the making of my improved shingle to the exact size shown on the drawing, but reserve the right to make it of smaller sizes, if desired. For example, it may be made in 12 105 inch or 9 inch lengths in widths suitably proportioned. In each case they are designed to be made from 36 inch widths of prepared roofing material with a view of using all the materials. The slits and marking can be varied and adjusted to the size of the shingle and the interlocking roof laid as heretofore described and shown. The size of the shingle herein shown and described is believed to be 110 most suitable for economy and utility, which is an important object of the invention.

It is to be observed that the newly improved shingle when laid in place as shown in Fig. 3, the side exposures are of a dove-tail 115 shape and are of sufficient size to make a figured roof that is ornamental and attractive in design for a roof of one color, and when shingles of different colors are used, will make a roof that will be artistic and pleasing to the eye. The shingles made of smaller size, it is believed will make the most artistic roof, if varied colors are used.

Having described my invention, I claim:—

1. A shingle of the class described, said 120

shingle rectangular in form, and means for interlocking said shingle with others of its kind, said means being a diagonal slit extending inwardly and upwardly from each side and from near the butt end of said shingle.

5 2. A shingle of the class described, said shingle made in rectangular form, side slits with rounded terminals extending inwardly and upwardly from near the butt end of said shingle, face markers on the top end of said shingle whereby it may be laid in lateral alinement, and side markers on the side edges of said shingle to indicate its horizontal overlap and alinement.

10 15 JESSE E. BERKHEIMER.
